UNITED STATES PATENT OFFICE.

JULIUS KAHN, OF YOUNGSTOWN, OHIO, ASSIGNOR TO TRUSSED CONCRETE STEEL COMPANY, OF DETROIT, MICHIGAN, A CORPORATION OF MICHIGAN.

FLOOR CONSTRUCTION.

1,250,588.

Specification of Letters Patent. Patented Dec. 18, 1917.

Application filed September 30, 1915. Serial No. 53,278.

To all whom it may concern:

Be it known that I, JULIUS KAHN, a citizen of the United States, residing at Youngstown, in the county of Mahoning and State 5 of Ohio, have invented new and useful Floor Constructors, of which the following is a specification.

This invention has reference to a metal-concrete or reinforced concrete floor construction, and among its important features 10 are the following:—troughs, preferably of pressed metal, (that constitute both carrying members and forms and are of sufficient length and stiffness to span the space between the floor beams and to support the 15 dead weight of the construction) together with a filling of reinforced concrete, by which is produced a very inexpensive construction capable of carrying both dead and live loads; flanges or flat surfaces forming 20 the upper and lower faces of the troughs and having tangs struck therefrom by which metal reinforcing or lath for the floor slab and ceiling may be conveniently secured in 25 position; ribbed metal lath extending across the upper surfaces of the troughs, said lath having the portions thereof between the ribs cut away above the troughs to allow the concrete filling to be readily poured or 30 shoveled into the troughs and at the same time to preserve an effective metallic connection between the portions of the lathing on opposite sides of a given trough, said ribs, when the lath is connected to the 35 flanges of the trough, also bracing the trough against lateral flexure; in combination with the concrete filled troughs and the floor slabs constructed as stated, continuity reinforcing members extending across the 40 upper portions of the floor beams and embedded in the slabs on either side; and pressed metal chairs resting on the troughs and embedded in the concrete for supporting the wooden floor sleepers to which the 45 floor is nailed. The invention further consists in the details of construction shown, described and claimed.

In the drawings, Figure 1 is a plan view showing the general relation of parts in one 50 embodiment of my invention. Fig. 2 is a section on the line 2—2 of Fig. 1. Fig. 3 is a section on the line 3—3 of Fig. 1. Fig. 4 is a perspective view of one of the troughs. Fig. 5 is a plan view showing the manner 55 of cutting the ribbed metal lath or rein-

forcing member over the girders. Fig. 6 is an end view corresponding thereto. Fig. 7 is a perspective view of the end of a trough with one of the nailing strip supports in position. Fig. 8 is a plan view showing the 60 manner of slitting the blank to form the support. Figs. 9 and 10 are perspective views showing modified forms of clips. Fig. 11 is a plan view of a blank slitted to form another modified support. Fig. 12 is an end 65 view of the clip bent from the blank shown in Fig. 11.

Similar reference characters refer to like parts throughout the several views.

In the embodiment of the invention 70 shown, 1 and 2 indicate, respectively, spaced columns of the reinforced concrete and incased metal types, the main member of the latter being of I cross-section. The first mentioned columns are joined by a reinforced concrete floor beam 3, and an incased floor beam 4 serves to connect the columns 2. It will be understood that the invention 75 is applicable to floors in which but one type of these columns and floor beams are found; and it will also be seen that the particular manner of reinforcing the columns 1 and beams 3, and the particular metal section incased in the column 2 and beams 4 may be varied within wide limits. For purposes of 80 illustration, I-beams 5 may constitute the main members of the beams 4; and the beams 3 may be reinforced by the bars 6. The necessary forms (not shown) are, of course, used in the construction of the floor 85 beams.

When the forms are in place, spaced troughs, preferably of pressed sheet steel (each of which includes a flat bottom 9, inclined or flaring sides 10, and outturned flat 90 flanges 11 from the edges of which the vertical stiffening flanges 12 may depend) are arranged to rest thereon at one end, their opposite ends being carried on the angle iron shelves 14 which are secured to the 100 I-beams 5 at an intermediate point in the depth thereof. The bottom 9 and flanges 11 preferably have struck therefrom the lath-holding tongues 15. While the troughs are shown perpendicular to the floor beams and 105 parallel to each other, they may be arranged differently to suit special conditions. At the side faces of the floor beams, the spaces between adjacent troughs are closed by sheet metal cap-plates 16 and 17 of suitable shape, 110

said plates being secured to the troughs in any desired manner; and between the cap plates, the troughs are covered by metal lath which includes the folded spaced ribs 18 that extend perpendicularly to the troughs and are connected by the relatively flat slashed body portions 19. Where the lath passes over the troughs the body portions are cut away as indicated at 20 in Fig. 5, the ribs, however, being retained.

One or more reinforcing bars 22, preferably having shear members 23, is placed in each of the troughs before the metal lath is laid in place, the ends of these bars extending into the floor beams to form anchorages; and continuity reinforcing bars 25 extend across the upper portions of the floor beams and terminate on either side at points some distance beyond the corresponding ends 20 of the troughs.

Resting on the troughs at intervals are pressed steel supports for the floor sleepers 26, each of the supports comprising the central body portion 28, the outwardly inclined bracing portions 29 (that terminate in split ends, one division 30 of which rests on the corresponding flange 11, the other division 31 extending down along the inner face of the corresponding side 10 and being riveted thereto at 31') and the upturned sleeper embracing clips 32, that may be perforated at 33 to receive nails.

The various members being in position, the concrete may be readily poured to complete the floor beam, joists and slabs, as is obvious, (the cap plates 16—17 serving to exclude the concrete from between the trough members) after which the ribbed metal or other ceiling lath 34 may be secured in position by the tangs and covered with plaster 35.

The nailing strip support shown in Fig. 9 differs from that heretofore described in that the part 30 is extended and bent downwardly at 36 along the flange 12, thus dispensing with the rivets 31'; and in Fig. 10 the same thing is accomplished by slotting the flanges 11 at 38 and inserting the division 39 of the support (which corresponds to the part 31) therethrough. The support shown in Figs. 11 and 12 is formed by cutting clips 40 out from the inclined brace portions 41 and slitting the lower ends of the latter to form the relatively wide divisions 42 that 55 rest on the flanges 11 and the narrow portions 43 which correspond to the parts 31—39.

To repeat: The ribs 18, when extended over and attached to the flanges of the trough, have a double function in that they not only form a continuous reinforcement across the trough but also greatly stiffen the flanges 11 thereof against lateral flexure.

Consequently the troughs may be made of 65 very thin metal (preferably pressed) of

strength substantially only that required to sustain the dead load of construction, which, since the trough acts both as a form for and a reinforcement of the concrete filling, results in a great saving of expense. The bars 25 in effect render the joists continuous over the floor beams, from which it follows that a further reduction in the cross section of the joists is secured. The nailing strip supports are also economical in that they are easily made and set in position, and also in that they constitute tension members which reinforce the upper portions of the joists against any tendency to bulge.

While the invention is of primary importance in connection with floors, it is clear that certain of its features are applicable to walls and the like; and it is also clear that many changes may be made in the details of the various embodiments thereof. I do not, therefore, wish to be limited otherwise than as indicated by the subjoined claims.

I claim:

1. A structure comprising a trough having an open side, metal lathing extending across the open side and being secured to and supported by the trough, said lathing comprising spaced ribs and reticulated body portions alternating with each other, the ribs extending continuously transversely across the trough, each end of the ribs being integral with the corresponding body portion of the lathing, parts of said body portions being removed at points where the lathing crosses the trough to form openings through which concrete may be inserted into the trough, said trough being filled with concrete to form a supporting member and said concrete inclosing the metal lathing to 105 form slabs on either side of the supporting member.

2. A structure comprising a trough having an open side, metal lathing extending across the open side, said lathing comprising spaced ribs and reticulated body portions alternating with each other, the ribs extending continuously transversely across the trough, each end of the ribs being integral with the corresponding body portion of the lathing, parts of said body portion being removed at points where the lathing crosses the trough to form openings through which concrete may be inserted into the trough, said lathing being secured to the trough in 120 such manner that the ribs bond the parts thereof together across the open side, whereby the trough is stiffened against lateral flexure, said trough being filled with concrete to form a supporting member and said concrete inclosing the metal lathing to 125 form a slab or panel on one side of the supporting member.

3. A floor construction comprising a plurality of spaced trough members having 130

open upper sides, metal lathing extending across and resting on the trough members, portions of said lathing being removed above the trough members to form free openings through which concrete may be poured, other portions of the lathing extending unbroken across the trough members, said trough members being filled with concrete to form floor joists and said concrete extending over and inclosing the metal lathing to form slabs between the joists.

4. A floor construction comprising a plurality of spaced trough members having flanges at their upper sides, said flanges having tongues struck therefrom, metal lathing extending across the trough members and secured thereto by the tongues, portions of said lathing being removed above the trough members to form free openings through which concrete may be poured, other portions of the lathing extending unbroken across the trough members, said trough members being filled with concrete to form floor joists and said concrete extending over and inclosing the metal lathing to form slabs between the joists.

5. A floor construction comprising a plurality of spaced trough members having open upper sides, ribbed metal lathing extending across and resting on the trough members, the ribs of the lathing being arranged transversely in respect to the trough members, portions of said lathing being removed above the trough members and between the ribs to form free openings through which concrete may be poured, other portions of the lathing extending unbroken across the trough members, said trough members being filled with concrete to form floor joists and said concrete extending over and inclosing the metal lathing to form slabs between the joists.

6. A floor construction comprising a plurality of spaced trough members having laterally extending flanges at their open upper sides, said flanges having tongues struck therefrom, ribbed metal lathing extending across the trough members and secured thereto by the tongues, the ribs of the lathing being arranged transversely in respect to the trough members, portions of said lathing being removed above the trough members to form free openings through which concrete may be poured, other portions of the lathing extending unbroken across the trough members, said trough members being filled with concrete to form floor joists and said concrete extending over and inclosing the metal lathing to form slabs between the joists.

7. A floor construction comprising a plurality of spaced trough members having open upper sides, metal lathing extending across and resting on the trough members, portions of said lathing being removed above

the trough members to form free openings through which concrete may be poured, other portions of the lathing extending unbroken across the trough members, said trough members being filled with concrete to form floor joists and said concrete extending over and inclosing the metal lathing to form slabs between the joists, reinforcing members extending longitudinally of the trough members near the bottoms thereof, said trough members being of strength sufficient to support the dead loads to which the floor is subjected during erection and constituting a form for the concrete, and together with the concrete fillings and reinforcing bars being of strength sufficient to carry the total load to which the floor is subjected at any time.

8. A floor construction comprising a pair of spaced metal-concrete beams, spaced sheet metal trough members extending between the beams and supported thereby, reinforcing rods extending longitudinally of the trough members and having their ends embedded in the beams, ribbed metal lathing supported by the flanges on the trough members, the ribs extending across the trough members, a portion of the rest of the lathing being removed over the trough members without severing the ribs to allow free pouring of concrete into the trough member and the trough members being filled with concrete, and said concrete extending to and inclosing the metal lathing to form slabs on each side of the troughs.

9. A floor construction comprising a pair of spaced metal-concrete beams, spaced sheet metal trough members extending between the beams and supported thereby, said trough members having open ends and an open upper side, reinforcing rods extending longitudinally of the trough members and having their ends embedded in the beams, and sheet metal cap plates extending across the space between the sides of adjacent troughs to constitute form-elements for the metal-concrete beams, and a concrete filling for the trough members, said filling being monolithic with the concrete of the beams.

10. A floor construction comprising a beam formed of a metal section incased in concrete, shelf members projecting from the metal section, a series of spaced sheet metal trough members resting on the shelf members and extending at an angle to the beam, and sheet metal cap plates extending across the space between the sides of adjacent troughs to constitute form-elements for the concrete of the beam.

11. A floor construction comprising a trough member having a bottom, sides, and flanges extending laterally outwardly from the upper edges of the sides, a wooden nail strip extending longitudinally of the trough member, means for supporting the

11. A nail strip from the trough member, said means comprising a member having a central portion on which the strip bears, inclined end portions that extend downwardly from the central portion to the upper inner edges of the sides of the trough members, said edges being split, one portion extending along the corresponding flange and the other extending downwardly along the inner face of the corresponding side of the trough.
12. A floor construction comprising a trough member having a bottom, sides, and flanges extending laterally outwardly from the upper edges of the sides, a wooden nail strip extending longitudinally of the trough member, means for supporting the nail strip from the trough member, said means comprising a member having a central portion on which the strip bears, inclined end portions that extend downwardly from the central portion to the upper inner edges of the sides of the trough members, said edges being split, one portion extending along the corresponding flange and the other extending downwardly along the inner face of the corresponding side of the trough, and clips struck upwardly at the ends of the central portion and embracing the sides of the nail strip.
13. A concrete floor construction comprising a wooden nail strip and a sheet metal support therefor, said support comprising a flat central portion on which the strip rests, clips at the ends of the central portion, said clips embracing the sides of the strip, divided end portions extending outwardly and downwardly from the central portion, and sheet metal trough members upon the opposite sides of which the end portions of the clips are respectively supported.
14. A floor construction comprising a thin metal trough having an open upper side through which a concrete filling may be inserted, the edges of said trough being provided with oppositely extending lateral flanges, a nail strip disposed longitudi-

nally and substantially centrally of the trough, and tension members extending crosswise of the trough at intervals and connecting the upper edges thereof, said tension members including upwardly projecting clips that embrace the sides of the nail strip, said trough being filled with concrete.

15. A floor construction comprising a thin metal trough having an open upper side through which a concrete filling may be inserted, the edges of said trough being provided with oppositely extending lateral flanges, a nail strip disposed longitudinally and substantially centrally of the trough, and tension members extending crosswise of the trough at intervals in broken convex lines, the upper portion of the tension members forming seats for the nail strips, said tension members including upwardly projecting clips that embrace the sides of the nail strip, said trough being filled with concrete, and said tension strips being embedded therein.

16. A structure comprising a metal trough having an open upper side, said trough constituting a form for a metal-concrete joist, and metal reinforcing extending continuously across said open upper side of the trough and being supported on said trough, said reinforcing being open above the trough to allow free pouring of concrete, said reinforcing also extending continuously on each side of the trough to constitute combined forms and reinforcing for slabs, and concrete filling said trough and extending laterally therefrom over the combined slab reinforcing and forms to constitute shallow slabs, whereby easy assembling of the reinforcing and easy pouring of the concrete, as well as increased strength of the structure, is insured, and whereby the use of false work is largely avoided.

In testimony whereof I sign this specification.

JULIUS KAHN.
